(57) **CLAIM**

The ornamental design for an impeller of water pump, as shown and described.

DESCRIPTION

The patent or application file contains a least one drawing executed in color. Copies of this patent or patent application publication with color drawings will be provided by the Office upon request and payment of the necessary fee.

FIG. 1 is a top, front and right side perspective view showing a first embodiment of our new design;

FIG. 2 is a bottom, front and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top, front and right side perspective view showing a second embodiment of our new design;

FIG. 10 is a bottom, front and right side perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a top, front and right side perspective view showing a third embodiment of our new design;

FIG. 18 is a bottom, front and right side perspective view thereof;

(Continued)

FIG. 19 is a front view thereof;
 FIG. 20 is a rear view thereof;
 FIG. 21 is a left side view thereof;
 FIG. 22 is a right side view thereof;
 FIG. 23 is a top view thereof;
 FIG. 24 is a bottom view thereof;
 FIG. 25 is a top, front and right side perspective view showing a fourth embodiment of our new design;
 FIG. 26 is a bottom, front and right side perspective view thereof;
 FIG. 27 is a front view thereof;
 FIG. 28 is a rear view thereof;
 FIG. 29 is a left side view thereof;
 FIG. 30 is a right side view thereof;
 FIG. 31 is a top view thereof;
 FIG. 32 is a bottom view thereof;
 FIG. 33 is a top, front and right side perspective view showing a fifth embodiment of our new design;
 FIG. 34 is a bottom, front and right side perspective view thereof;
 FIG. 35 is a front view thereof;
 FIG. 36 is a rear view thereof;
 FIG. 37 is a left side view thereof;
 FIG. 38 is a right side view thereof;
 FIG. 39 is a top view thereof;
 FIG. 40 is a bottom view thereof;
 FIG. 41 is a top, front and right side perspective view showing a sixth embodiment of our new design;
 FIG. 42 is a bottom, front and right side perspective view thereof;
 FIG. 43 is a front view thereof;
 FIG. 44 is a rear view thereof;
 FIG. 45 is a left side view thereof;
 FIG. 46 is a right side view thereof;
 FIG. 47 is a top view thereof;
 FIG. 48 is a bottom view thereof;
 FIG. 49 is a top, front and right side perspective view showing a seventh embodiment of our new design;
 FIG. 50 is a bottom, front and right side perspective view thereof;
 FIG. 51 is a front view thereof;
 FIG. 52 is a rear view thereof;
 FIG. 53 is a left side view thereof;
 FIG. 54 is a right side view thereof;
 FIG. 55 is a top view thereof;
 FIG. 56 is a bottom view thereof;
 FIG. 57 is a top, front and right side perspective view showing a eighth embodiment of our new design;
 FIG. 58 is a bottom, front and right side perspective view thereof;

FIG. 59 is a front view thereof;
 FIG. 60 is a rear view thereof;
 FIG. 61 is a left side view thereof;
 FIG. 62 is a right side view thereof;
 FIG. 63 is a top view thereof; and,
 FIG. 64 is a bottom view thereof.
